Patented Nov. 19, 1918.

UNITED STATES PATENT OFFICE.

JOHN GOOD, OF BROOKLYN, NEW YORK.

MATCH-BOX HOLDER.

1,285,126.

Specification of Letters Patent. Patented Nov. 19, 1918.

Application filed March 29, 1915, Serial No. 17,717. Renewed May 2, 1918. Serial No. 282,158.

To all whom it may concern:

Be it known that I, JOHN GOOD, a citizen of the United States, residing in Brooklyn, in the county of Kings, State of New York, have invented the following-described Improvements in Match-Box Holders.

The improvements concern the convenience of use and manufacture of match-box holders or match-box trays, being more particularly directed to the construction of such a device capable of being manufactured economically out of light sheet metal, and which holds the boxes firmly while at the same time being constructed so as to facilitate their insertion and removal.

In the drawings,

Figure 1 is a side elevation, with parts in section, of one from of the improved holder with a match-box thereon;

Fig. 2 is a top plan of such holder;

Fig. 3 a partial section on line III—III of Fig. 2;

Fig. 4 represents a sectional detail of the box bracket;

Figs. 5 and 6 represent a modified construction—Fig. 5 being a fragmentary sectional side elevation, and Fig. 6 a similar elevation at a different angle; and Fig. 7 is a fragmentary sectional side elevation of a further modification.

In the various figures the numeral 1 represents the base or tray which is illustrated in the present case as formed of sheet metal with an upstanding boss 2 at its center. The form of the base may be varied as desired, and it is not material whether it be constituted simply as an ornamental base or as a tray or as the part of some other receptacle, and it is not of consequence to the invention whether it be made of sheet metal, as indicated, or otherwise.

The upper face of the boss 2 is flat, and to it is secured the bracket 3 which consists of a strip of spring metal of a width slightly less than the inside depth of the cover of an ordinary safety match-box. One end of this strip is secured by solder, spot-welding or otherwise, to the flat top of the boss 2 as indicated at 4, and the rest of the strip is bent substantially as shown in Fig. 1 so that the cover of the match-box can be placed over it. The extreme end 5 of the bracket strip serves as a thumb-piece by which the opposite sides 6 and 7 of the bracket can be pressed together to allow the cover to be slipped in place thereover,—re-

lease of the thumb-piece permitting the side members 6 and 7 to expand against the inside of the cover, holding it firmly in position. If desired, a series of barbs, or prongs 8 may be formed on the cover engaging faces of the side-member 6 to increase the security with which the cover is held, but these are not ordinarily necessary where the spring strip is of sufficient resilience to exert an adequate pressure upon the box cover. It will be understood that the match-box illustrated in the drawings is the well known common safety match-box consisting of the hollow rectangular sliding cover as shown at 9, having prepared surfaces 10 on its narrow sides upon which to strike the match, with a box-body 11 therein which may rest upon or against the box-bracket 3 as shown in the drawings, exposing the upper ends 15 of the matches. The end of the box-body is commonly broken off as indicated. The bracket holds the box to the base or tray at an inclination, so that the box appears to be resting on one corner with one of its 20 prepared sides exposed upwardly and at an angle of about 45 degrees from vertical. In this position the pressure of a match scratched upon such surface will result principally in a downward pressure component in the tray, creating a frictional effect between the bottom of the tray and the surface on which it rests, which will prevent lateral movement of the tray thereon, as well as any tendency for the device to tip 25 over. The necessity of making the tray as a heavy casting or of loading it with lead or of facing the bottom of it with felt or rubber, as is commonly done, is thus entirely eliminated.

In the form shown in Figs. 5 and 6 the box-bracket is formed with a terminal spring clip 14 by which it can be snapped into a suitable slot in the face of the boss 2, being thus held firmly in position thereon. By compressing the spring clip the bracket can be removed from the tray. The side member 6 of the bracket is reversely bent so as to occupy a position within the box cover, the thumb-piece 5 being thus brought to a 30 position entirely concealed by the box cover.

In Fig. 7 the box bracket is permanently secured to the base, and the thumb-piece 5 is brought downwardly, and projected through an aperture in the boss 2 so as to 35 be accessible from the lower side of the tray. Thereby the entire bracket is substan-

2
tially concealed from view within the box cover.

In all of the forms above described the box is securely and removably held to the tray or base, with the matches therein sufficiently exposed to permit their ready removal, as will be evident, and since the device consists of but two pieces and can obviously be made at a minimum of cost, it is therefore serviceable for advertising purposes.

Having described the invention, I claim the following:

1. A holder for safety match-boxes having a prepared striking surface on one face, consisting of a base or support, and an expanding box-bracket thereon having a thumb piece for contracting it.

2. A holder for safety match-boxes of the

kind described, comprising a base support, an expandible box bracket thereon adapted to engage the inside of the box cover, and a concealed thumb-piece adapted for operation to contract the bracket for removing and replacing the box thereon.

3. A safety match box holder as described, comprising a base and an expandible bracket thereon, formed of an elastic strip with one end free and constituting a thumb piece whereby the box may be released.

In testimony whereof I have signed this specification in the presence of two witnesses.

JOHN GOOD.

Witnesses:

G. A. TAYLOR,
N. L. GRANT.
